LEVELING MACHINE

Arthur Ernest Jerram and Cyril Catley Sheffield, Leicester, England, assignors to United Shoe Machinery Corporation, Paterson, N. J., a corporation of New Jersey

Application September 1, 1937, Serial No. 161,984
In Great Britain September 23, 1936

8 Claims. (Cl. 12—34)

This invention relates to machines for applying pressure to the bottoms of shoes and more particularly to machines of the type in which a shoe support and a pressing or leveling tool, such as a roll, are relatively movable to cause the roll to operate progressively along the bottom of a shoe.

Well-known automatic machines of the above-mentioned type include in their organization a carrier for pressing the roll against the shoe and for variably tipping the roll relatively to the shoe support to position the roll in proper relation to different portions of the bottom of the shoe. The roll is usually concave laterally of the shoe, and its tipping movements render it especially effective on different laterally convex portions of the shoe bottom. In leveling the bottoms of shoes, it has been found that it is sometimes difficult to produce as even and smooth a shoe bottom as desired particularly if there are irregularities in the sole such as bunches caused by the unevenness of the shoe materials between the outsole and the insole since such irregularities are difficult to eliminate by the action of the roll. We have found that by transferring the area of contact of the roll with the sole rapidly widthwise of the shoe as the roll traverses the bottom of the shoe, the pressure of the roll will be applied to all portions of the sole to level it effectively regardless of any small irregularities that may exist in the sole. Accordingly, the present invention provides means for thus operating a leveling roll, so as to apply to the sole alternately in different locations widthwise of the shoe rapidly repeated pressure impulses heightwise of the shoe in the course of the leveling operation. In the construction shown, the leveling roll is mounted to rotate freely on a continuously driven supporting shaft between which and the roll there is interposed a bushing which is keyed to the shaft and the periphery of which is inclined relatively to the axis of the shaft to cause the geometrical axis of the roll to travel around the surfaces of two cones the apexes of which are located substantially midway between the ends of the roll. Thus, the ends of the roll have equal circular movements in opposite directions, one end of the roll moving upwardly as the other end of the roll moves downwardly so that as the roll traverses the bottom of the shoe the pressure of the roll is transferred rapidly widthwise of the shoe to different portions of the sole to level it. In effect, the roll is tipped at a rapid rate laterally of the shoe in opposite directions alternately about an axis extending lengthwise of the shoe and located substantially midway between the ends of the roll. Thus, any

small irregularities that may exist in the sole are each treated repeatedly by the roll with the result that such irregularities are properly eliminated and the desired transverse curvatures are imparted to the different portions of the sole. 5

The invention in its different novel aspects will now be more particularly described by reference to the accompanying drawing and thereafter pointed out in the claims.

In the drawing,

Fig. 1 is a view in side elevation of a portion of a machine in which the present invention is embodied; and

Fig. 2 is a view partly in front elevation and partly in section of a portion of the machine 15 shown in Fig. 1, illustrating particularly the mounting of the leveling roll.

Since the invention is illustrated as applied to a leveling machine of a well-known type, only such parts of the machine as it is necessary to 20 refer to for an understanding of the invention are shown and will be described in detail. Features of the general organization of machines of this type are disclosed in various prior United States Letters Patent including Letters Patent No. 25 1,667,761, granted on May 1, 1928, on an application of E. E. Winkley and H. A. Davenport. It will be understood that the machine includes an automatically controlled leveling roll 10 and a shoe support or jack which, in the power operation of the machine, is moved automatically in directions lengthwise of the shoe to cause the roll to operate progressively along the bottom of the shoe. The jack comprises a toe post 12 and a heel post 14 which are pivoted together for relative adjustment for shoes of different sizes by means of a threaded adjusting rod 16 which moves the heel post toward or from the toe post so that the toe ends of shoes of different sizes will be presented in substantially the same relation to the roll 10. The jack, as a whole, is operatively movable about the axis of a shaft 18 on which the toe post is mounted, and power operated means (not herein shown) is provided for imparting to the jack oscillatory movements about this axis 30 35 40 45 50 55 to carry the shoe rearwardly and forwardly under the leveling roll. The toe and heel posts are provided with means for supporting a shoe and last for the leveling operation. Mounted on the toe post 12 is a toe rest comprising a block 20 having secured to it a rubber pad 22 for engaging the toe end of the shoe. The heel post 14 at its upper end supports a block 24 carrying a spindle (not shown) arranged to enter the spindle hole in the heel end of the last. The roll 10 is mounted on a

holder 26 which is supported on a roll carrier 28 pivotally mounted as heretofore on the frame of the machine for swinging movements in a vertical plane to press the roll against the shoe with different degrees of pressure on different portions of the shoe bottom. It will be understood that the holder 26, also as heretofore, is so controlled as to tip the roll 10 about an axis extending lengthwise of the shoe in time relation to the movements of the jack and thus to position the roll for operating in the desired manner on different portions of the sole.

For purposes of this invention there is provided means for operating the leveling roll 10 to impart to the sole in different locations widthwise of the shoe, alternately, pressure impulses heightwise of the shoe in the course of the leveling operation. In the construction shown the holder 26 carries a shaft 30 upon which the roll 10 is supported, and between the shaft 30 and the roll there is provided a bushing 32 secured to the shaft by a key 33 and having its peripheral surface inclined at a small angle, preferably one degree, to the axis of the shaft. The shaft 30 is held against endwise movement in the holder 26 by spaced collars 34 pinned to the shaft and engaging the opposite end faces of the holder. In order that the roll 10 may be free to rotate on the bushing 32 by engagement with the bottom of the shoe as the jack is swung rearwardly and forwardly beneath the leveling roll, there are provided, between the roll and the bushing, ball bearings 36 which are held against movement lengthwise of the bushing by means of a spacing member 38 and flanges 40 on the bushing. In the illustrated construction the shaft 30 and the bushing 32 are continuously driven at a high rate of speed, preferably about 1700 R. P. M., by means of a motor 42 mounted on the holder 26 and connected by a belt 44 to a pulley 46 fast to one end of the shaft. It will be understood that by reason of the inclination of the peripheral surface of the bushing 32 the geometrical axis of the leveling roll is inclined relatively to the axis of the shaft 30, the construction being such that as the shaft and bushing are rotated the geometrical axis of the roll travels around the surfaces of two cones the apexes of which are located substantially midway between the ends of the roll. The ends of the roll 10 thus have equal circular movements in opposite directions, one end of the roll moving upwardly as the other end of the roll moves downwardly so that the roll imparts to the sole in different locations widthwise of the shoe alternately pressure impulses heightwise of the shoe as the roll traverses the bottom of the shoe. In effect the roll is tipped laterally of the shoe at a rapid rate about an axis extending lengthwise of the shoe and located substantially midway between the ends of the roll. This causes the pressure of the roll to be transferred rapidly widthwise of the shoe so that any small irregularities that may exist in the sole are each treated repeatedly by the roll with the result that such small irregularities are properly eliminated and the desired transverse curvatures are imparted to the sole.

The normal period of time for leveling a shoe of average length in a machine of the type herein shown is approximately thirteen seconds, during which time the shoe makes two complete traversing movements between the toe end of the sole and the heel breast line and two complete shorter traversing movements between the

heel breast line and the ball line. By rotating the shaft 30 and the bushing 32 at the rate of speed above indicated substantially eight complete turning movements are imparted to the shaft and bushing to transfer the pressure of the roll laterally of the shoe during each inch of traversing movement of the shoe, and approximately seventy complete turning movements are imparted to the shaft and bushing during each traversing movement of the shoe from the toe end of the sole to the heel breast line. As previously pointed out, not only is the roll thus caused to act repeatedly on each small irregularity that may exist in the sole, but substantial assurance is afforded that the pressure of the roll will be transferred to all portions of the sole to level it without any danger of damage to the sole such as might result if the roll were driven or caused to drag across the surface of the sole.

Having described the invention, what we claim as new and desire to secure by Letters Patent of the United States is:

1. In a machine for applying shaping or leveling pressure to the bottoms of shoes, the combination with a shoe support and a leveling roll relatively movable in directions lengthwise of a shoe on said support to apply pressure progressively to the sole of the shoe, said roll being rotatable in the leveling operation in response to engagement of the shoe therewith, of means for operating said leveling roll to apply to the sole in different locations widthwise of the shoe alternately pressure impulses heightwise of the shoe in the course of the relative movement of the roll and support in each direction.

2. In a machine for applying shaping or leveling pressure to the bottoms of shoes, the combination with a shoe support and a leveling roll relatively movable in directions lengthwise of a shoe on said support to apply pressure progressively to the sole of the shoe, of a power driven member arranged to support said roll and rotatable relatively thereto for imparting to said roll rapidly repeated tipping movements laterally of the shoe to transfer the pressure of the roll back and forth widthwise of the shoe throughout the operation of the roll on the shoe.

3. A leveling machine, having in combination, a shoe support, a leveling roll for applying rolling pressure progressively to the sole of a shoe on said support in response to movement of the support relatively to the roll in directions lengthwise of the shoe, said roll being mounted for tipping movements laterally of the shoe about an axis extending lengthwise of the shoe and located substantially midway between the ends of said roll, and power-operated means for imparting to said roll a plurality of rapidly repeated tipping movements about said axis during the operation of the roll on both the forepart and shank portions of the shoes.

4. A machine for applying shaping or leveling pressure to the bottoms of shoes having, in combination, a shoe support, a leveling roll for applying pressure progressively to the sole of a shoe on said support in response to movement of said support in directions lengthwise of the shoe, a carrier for pressing the roll against the shoe, a shaft supporting the roll on said carrier, means for rotating said shaft, and a sleeve interposed between said shaft and the roll, said sleeve being connected to said shaft for turning movement with the shaft and having its periphery inclined relatively to the axis of said shaft to cause tipping

movements to be imparted to said roll in opposite directions alternately in each rotation of the shaft to transfer the pressure of the roll laterally of the shoe in the course of the leveling operation.

5. 5. A machine for applying shaping or leveling pressure to the bottoms of shoes having, in combination, a shoe support, a leveling roll for applying pressure progressively to the sole of a shoe on said support in response to movement of the support 5
10 in directions lengthwise of the shoe, a carrier for pressing the roll against the shoe, a shaft supporting the roll on said carrier, means for rotating said shaft, and a sleeve interposed between said shaft and the roll, said sleeve being connected to
15 said shaft for turning movement with the shaft and having its periphery inclined relatively to the axis of said shaft to cause the geometrical axis of said roll to travel around the surfaces of two cones the apexes of which are located substantially mid-
20 way between the ends of the roll.
6. In a machine for applying shaping or leveling pressure to the bottoms of shoes, the combination with a shoe support and a leveling roll relatively movable in directions lengthwise of a shoe
25 on said support to apply pressure progressively to the bottom of the shoe, of mechanism for imparting automatically to said roll rapidly repeated tipping movements in opposite directions about an axis extending lengthwise of the shoe throughout
30 the operation of the roll on the shoe, said roll being rotatable in the leveling operation in response to engagement of the shoe therewith.

7. In a machine for applying shaping or leveling

pressure to the bottoms of shoes, the combination with a shoe support and a leveling roll relatively movable in directions lengthwise of a shoe on said support to apply pressure progressively to the bottom of the shoe, of a shaft extending through the roll to support it with the axis of the shaft in angular relation to the axis of the roll, power-driven means for rotating said shaft, and mechanism for imparting to the roll in the course of the leveling operation rapidly repeated tipping movements 10 about an axis extending lengthwise of the shoe by the rotation of said shaft, the roll being rotatable relatively to said shaft in response to engagement of the shoe therewith.

8. In a machine for applying shaping or leveling pressure to the bottoms of shoes, the combination with a shoe support and a leveling roll relatively movable in directions lengthwise of a shoe on said support to apply pressure progressively to the bottom of the shoe, of a shaft extending through the roll with the axis of the shaft in angular relation to the axis of the roll, power-driven means for rotating said shaft, and a bearing support for the roll connected to the shaft to turn therewith and so formed as to cause the 25 ends of the roll to describe circles of greater diameter than said ends in the course of the leveling operation, the roll being rotatable relatively to said shaft in response to engagement of the shoe therewith.
